(57) **CLAIM**

The ornamental design for a wall mountable accessory, as shown and described.

DESCRIPTION

FIG. 1 is a left, top, front perspective view of a wall mountable accessory embodying my new design;
FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a front elevational view of a wall mountable accessory of another embodiment of my new design, the perspective, front, top, left side, right side, bottom and rear views of this embodiment being mirror images of the respective views shown in FIGS. 1-7;

FIG. 9 is a left, top, front perspective view of a wall mountable accessory of another embodiment of my new design;

FIG. 10 is a front elevational view thereof;

FIG. 11 is a left side elevational view thereof, the right side elevational view being a mirror image of the left side shown;

FIG. 12 is a top plan view thereof;

FIG. 13 is a bottom plan view thereof;

FIG. 14 is a rear elevational view thereof;

FIG. 15 is a left, top, front perspective view of a wall mountable accessory of another embodiment of my new design;

FIG. 16 is a front elevational view thereof;

FIG. 17 is a top plan view thereof, the bottom plan view being a mirror image of the top shown;

FIG. 18 is left side elevational view thereof, the right side elevational view being a mirror image of the left side shown;

FIG. 19 is a rear elevational view thereof;

FIG. 20 is a left, top, front perspective view of a wall mountable accessory of another embodiment of my new design;

FIG. 21 is a front elevational view thereof;

FIG. 22 is a top plan view thereof, the bottom plan view being a mirror image of the top shown;

FIG. 23 is left side elevational view thereof, the right side elevational view being a mirror image of the left side shown; and,

FIG. 24 is a rear elevational view thereof.

The broken line representations of seam lines, bar environment or mounting structures in FIGS. 1-3, 7-8, 14-22 and 24 are for the purpose of illustration only, and form no part of the claimed design.
